UNITED STATES PATENT OFFICE.

LEONARD D. DAVIS, OF ERIE, PENNSYLVANIA.

APPARATUS FOR CROSS-ROLLING ROUND BODIES

1,123,179.

Specification of Letters Patent.

Patented Dec. 29, 1914.

Application filed July 12, 1912. Serial No. 709,614.

Renewed November 20, 1914. Serial No. 573,246.

To all whom it may concern:

Be it known that I, LEONARD D. DAVIS, a citizen of the United States, and a resident of Erie, Pennsylvania, have invented 5 certain new and useful Improvements in Apparatus for Cross-Rolling Round Bodies, of which the following is a specification, accompanied by drawings.

The invention is particularly applicable 10 to the cross rolling of tubes, such as steel tubes in the heated state, or copper or other more ductile metal in a cold state, upon mandrel bars to reduce the wall thickness, but is also applicable to the rolling and reduction 15 of solid billets or bars and is not limited to the particular use herein described.

In my copending application No. 727,208, filed October 22nd, 1912, improvements in process are described and claimed which can 20 be carried out by the present apparatus; and this present application is directed to improvements in apparatus.

The object of the invention is to effect the reduction by cross rolling in a rapid and 25 efficient manner without undue strains of the metal and preferably by means of obliquely-acting concave rolling surfaces which encircle the work piece and embrace it simultaneously from a plurality of different lat- 30 eral directions.

In the preferred form of the invention helical rolling surfaces are employed, so 35 that the points of contact sweep along the billet or work piece and also along the helices.

In my previous Patent No. 928,946 of July 27th, 1909, rolling helices are shown and described, the axes of which are parallel with the axis of the pass. It will be 40 seen that some features of the present invention form an improvement upon this prior patent, but other features are independent thereof, as will be clear from the claims herein.

The present invention in its preferred 45 form provides a plurality of concave rolling bodies the axes of which are inclined to the axis of the pass and also offset therefrom, and the obliquity and offset are so arranged 50 that the desirable increase in the feeding effect, as the work piece is reduced in section and consequently travels faster toward the exit end of the pass, is produced.

Certain other features of the invention will be made apparent in connection with 55 the description of the preferred embodiment of it which follows.

In the accompanying drawings, Figure 1 is a side view of a rolling mill embodying the present invention; Fig. 2 is an end view 60 of the same viewed from the exit end; Fig. 3 is an end view of the same viewed from the entrance end; Fig. 4 is a view on larger scale of the same machine mainly in central vertical longitudinal section; Fig. 5 is a 65 diagram showing in side elevation the arrangement of the four axes of the rolling bodies in respect to the axis of the pass; Fig. 6 is a diagram showing an end view of the same arrangement of the four roll axes; 70 Fig. 7 is a sectional view of the four rolling helices of the same mill; Fig. 8 is a view showing a modification wherein two rolling rings are used in place of one helix, but at a sacrifice, as will be explained, of some of 75 the advantages of oppositely-acting inter-coiled helices; Figs. 9 and 10 are detail end views of a fragment of a helix, respectively near the entrance and exit end of the pass, looking from the exit end of the mill; Fig. 80 11 is an end view corresponding to Fig. 9, but showing a closed rolling ring corresponding in position and obliquity with Fig. 9, and viewed from the exit end of the mill; Fig. 12 is a side view of Fig. 11 from the 85 lefthand side; Fig. 13 is a view looking upward at Fig. 11 along the line joining the two figures through the point of contact; Fig. 14 is a view corresponding to Fig. 11, but showing a ring instead of a portion of a 90 helix near the exit end of the pass, viewed from the exit end; Fig. 15 is a view of the same from the lefthand side of Fig. 14.

The main frame of the machine preferably consists of a substantial base 10 and three 95 uprights 11, 12, 13.

The uprights 12 and 13 support the bearings of a hollow shaft 14, on which are rigidly secured the driven belt pulley 15 and a driving toothed pinion 16. The axis of the 100 pass extends through the hollow shaft 14.

To the upright 12 are pivoted or hinged by substantial belts 20, which lie symmetrically about the pass in a plane perpendicular to the pass, four angularly adjustable 105 carriers 21, preferably of troughlike sec-

tion to afford great strength, as shown. These carriers are angularly adjustable about their hinges by means of strong set screws, mounted in the upright 11. As shown, there is one inwardly acting set screw 22 and two outwardly-acting set screws 23 acting on the end of each carrier 21, for adjusting and rigidly securing the end of the carrier in respect to the upright 11.

19 Mounted in each of the four carriers in three substantial bearings, as shown, is a stiff shaft 25. These shafts are driven by the four driven gears 26 secured rigidly upon them and driven by the central gear 16.

20 The axes of these shafts 25 may lie in such a position that if projected toward the exit end of the machine they converge to a common point in the axial line of the pass, so that the gears 16 and 26 may be true bevel gears. Manifestly, the gears should be de-

21 signed for the mean working position of the adjustable carriers 21, although the adjustment of these carriers will not materially interfere with the proper action of the gears.

22 Each of the shafts 25 has secured rigidly upon it a pair of gears 27.

23 Each of the carriers 21 is provided with a pair of annular bearing frames 31, each composed of two halves or castings bolted together and to the longitudinal member of the carrier 21. Each of these annular bearing frames 31 affords an annular journal bearing for an annular gear wheel 33, the teeth of which mesh with and are driven by the corresponding gear 27. The annular frames are widened near their point of attachment to the longitudinal members of the carriers 21, so as to partly inclose and protect the gears 27, as shown. The gears 33 are preferably of the cross section plainly shown in Fig. 4, affording shoulders on either side of the row of gear teeth, so that these shoulders and the bases of the gear teeth form respectively the cylindrical jour-

24 nal surfaces and the end-thrust surfaces of the gears. The imaginary axes of these gears and of the roll bodies that are mounted to turn with them respectively are coincident, and they are parallel with the re-

25 spective inclined driving shafts 25 which

26 activate them; but the axes are offset from

27 the axis of the pass so as not to intersect the

28 same, in order to give a feeding effect, as

29 will presently be made clear.

30 Rigidly bolted or otherwise secured to the inside of each pair of annular gears 33 is a heavy bar or roll support 35 which directly carries the rolling bodies which turn therewith. These four bars are preferably made

31 in irregular shapes to afford clearance without necessitating unduly large inside diameters of the annular gears 33, which, it will be seen, are respectively concentric with only one of the four bars. These bars are

32 shown in end view in Fig. 3, and two of

them in section in Fig. 4. To each of these bars is secured rigidly at two or more points one of the four intercoiled rolling helices 41, 42, 43, 44. The bolts by which the bars 35 are secured to the annular gears are 70 shown in one instance at 36 in Fig. 4; those of the bars in cross section are obviously not in the plane of section and not, therefore, seen in the figure. Likewise, the bolts that secure the rolling bodies to the bars are not 75 shown, but, for the purposes of understanding the invention, it is obvious that the rolling bodies could be electrowelded or secured in any other desirable manner rigidly to the bars, although preferably they should be 80 readily detachable.

Each of the four helices makes preferably somewhat more than one complete turn around the pass. Each should make contact with the work piece at one of its own 85 ends before its other end passes out of contact with the work piece, assuming, of course, that the work piece is of sufficient length.

As shown in Figs. 4 and 7, two of the helices 42 and 44 form a pair which act on 90 the work piece at diametrically opposite points, and the same is true of the other pair 41 and 43.

It will be obvious that the contact of each helix on the work piece sweeps from end to 95 end of the helix. It will also be obvious from consideration of Figs. 5 to 15, inclusive, that the point of contact of a helix with the work piece sweeps around the work piece through an angle of somewhat less than 100 ninety degrees, that is to say, less than a quarter turn.

The preferred arrangement of the helices and their axes is as follows: The billet and the helices rotate righthandedly; that is to 105 say, as viewed from the exit end of the machine, lefthandedly or counterclockwise. Also the shape of each helix is righthanded, like the thread of an ordinary screw or corkscrew, though this could be reversed without reversing the direction of rotation. The axis of each helix, which is of course an imaginary line, inclines toward the axis of the pass from front to rear, and approaches most nearly to the axis of the pass at the 110 exit end slightly beyond the end of the helix, as shown in Figs. 5 and 6.

In Fig. 5 the lines 41^a, 42^a, 43^a and 44^a are the respective axes of the helices, 45^a being the axis of the pass. The cross lines *b* and *c* indicate the entrance and exit ends of the pass through the helices. At *d*, beyond the exit end of the pass, the four axes of the helices approach most closely to the axis of the pass; and, consequently, the common perpendiculars between the axis of the pass and the respective axes of the helices intersect at this point *d*, as will be clear from Figs. 5 120 and 6 considered together. It will be seen that the four axes are arranged symmetrically 125

130

around the axis of the pass. We may, therefore, confine attention to one helix, for example, 44, the axis of which runs downward toward the front of the machine. 5 Viewed from the exit end of the pass, the axis 44^a lies to the right of the axis of the pass, as seen in Fig. 6, where, manifestly, the common perpendicular between these two axes is not fore-shortened and correctly 10 measures the offset of the axis of the roll from the axis of the pass. Obviously also, Fig. 5, being a side elevation viewed lengthwise of the said common perpendicular, shows the axis 44^a as apparently crossing the axis of the pass at the point *d*. Furthermore, both these axes, being parallel with the plane of the drawing in Fig. 5, correctly show the angle of inclination or obliquity of the axis 44^a to the axis of the pass. 15 In order to analyze and resolve the oblique rolling action of any point of contact into its components lengthwise of the pass and transverse to the pass, it is convenient to consider any contact point of the helix as 20 corresponding to a point of a ring-shaped rolling body turning on the same axis. Thus, for example, in considering the helix 44 in Fig. 7, it is convenient to compare it with two rings, as in Fig. 8, turning on a 25 similarly arranged axis and corresponding to the two ends of the helix.

In consideration of Figs. 9 to 15, it will be clear that a ring or similarly concave rolling body will make contact with the work piece approximately at a point opposite to the center of the ring in respect to the center of the work piece. Thus, for the axis 44^a in Fig. 5, which is a side elevation, the contact point of a ring concentric with the axis 44^a would be at the top of the work piece if the figure were continued toward the left hand and the ring located at a great distance toward the left, but even at the plane of the line *b*, for reasons which will 30 be immediately apparent from considering Figs. 9 and 11, the contact point will be very nearly at the top of the billet. On the other hand, as the common perpendicular at *d* is approached, the point of contact of such a ring will approach to the side toward the observer of Fig. 5, that is to say, toward the lefthand side as viewed from the rear, as will be apparent from Figs. 10 and 14. 35 Where the angle of inclination or obliquity is small, as in Fig. 5, and the offset is small as compared with the radius of the billet or tube, it will now be manifest that as we progress from the entrance to the exit of the pass the transverse component of the speed 40 of rotation of the rolling body as it makes contact with the work piece diminishes, principally by reason of the diminishing radius of the interior of the ring or helix, whereas the longitudinal component or feed 45 component of the rolling action increases

progressively as the common perpendicular is approached, principally by reason of the increasing angle at which the cross rolling takes place, which angle would reach its maximum beyond the exit end of the pass 70 adjacent to the common perpendiculars at *d*. This increase of the feeding effect is somewhat lessened, of course, by the decreased internal radius of the ring or helix toward the exit end of the pass, but the effect of the 75 changing angle of the cross rolling greatly predominates over the effect caused by the decrease of radius.

To illustrate these principles of operation, Figs. 9 to 15 will serve. In Fig. 9 a fragment of the helix 44 is shown in contact with the billet 51 near the entrance to the pass. The axis of the pass is, of course, at the center of the billet. The axis of the helix is shown by the line 44^a, and the point *f* on this line is the center of motion of the contact point of the helix about its axis 44^a. Consequently, drawing a line from the point *f* across the center of the billet and projecting it beyond the other side will give the line *g* passing through the point of contact. Obviously, this will be near the uppermost line of the billet. Fig. 11 shows a complete ring making contact at a similar point in a similar way. It will be seen from the associated views 12 and 13 that there is but little skew or obliquity of the rolling motion. The motion at the point or area of rolling contact is nearly transverse to the length of the billet with a little forward 80 feed due to the slight obliquity. In Fig. 13 both the ring and the work piece are viewed perpendicularly to the point or area in contact, and, therefore, the obliquity, skew, or feed angle is made correctly apparent without any appreciable distortion or fore-shortening in the drawing. Consequently, it will be manifest that this obliquity, skew or feed angle between the direction of motion of the points of the roll in contact with the billet and a plane perpendicular to the axis of the billet is, at the entrance of the pass, but a small fraction of the obliquity at the exit end, and a still smaller fraction of the obliquity or inclination of the axis 85 of the roll to the axis of the pass.

The conditions near the exit end of the pass are illustrated by Figs. 10, 14 and 15. Here the point *f'* in the axis 44^a of the roll, which is the point around which the point of contact of the roll on the billet is moving, is approximately beside the axis of the pass, instead of well beneath it; and, consequently, the line *f'*—*g'*, extending from the point *f'* perpendicularly through the axis of the pass 100 and the point or area of contact, shows that such point or area of contact is on the side of the billet, as is shown in Figs. 10 and 14, instead of at the top of the billet, as at the entrance end of the pass. Fig. 15, being a 105

side view of 14, shows that the direction of motion of the point of the roll that is in contact with the billet and which is only slightly above the level of the axis of the pass, as shown by Fig. 14, is inclined from the perpendicular plane across the pass nearly and substantially as much as the inclination or obliquity of the axis of the roll. If the ring C were acting opposite to the point d of the pass, Fig. 5, instead of at the plane c, Fig. 5, the condition would be reached wherein the line f'-g' lies horizontally in the plane of the axis of the pass and the feed angle or angle of obliquity of the rolling motion reaches the full measure of the angle of obliquity between the axis of the roll and the axis of the pass.

As already pointed out, in the use of a helix, unlike a ring, the point or area of contact between the helix and the billet or work piece sweeps along the pass, as well as shifting around the pass, as seen from Figs. 9 and 10.

I prefer to design the rolls, whether helices or rings are used, of the rounded cross section of rolling face shown in Figs. 7 and 8. The internal radius of the helix at each point I prefer to proportion for an even reduction of the wall or radius of the work piece between the entrance and the exit end of the pass for about three-quarters of the length of the helices, designing the last quarter for action on a uniform radius of billet or work piece, so as to give a substantially smooth cylindrical surface to the work piece by the time it issues from the helices. Preferably, also, the helices, as well as their axes, are symmetrically placed around the pass, so that all four of the helices press upon the work piece at any instant in the same transverse plane. This is best seen in Fig. 3. It is also shown in Figs. 4 and 7.

In Fig. 4, the helices are shown making contact with the billet at approximately their mid-length. In Fig. 7, they are shown rotated about half a turn, so as to make contact at approximately the entrance end of the pass under the conditions explained in connection with Fig. 9. If two rings 47 are employed in place of one helix, as shown in Fig. 8, it will be seen that there will be a constant rolling action of each ring, instead of a sweeping action of the contact point along the pass. If rings are used in place of the helices, it will be clear that they cannot practicably be placed so that a plurality of them act upon the billet simultaneously at the same cross section. In Fig. 4, two rolling rings or annular rolling bodies 55 and 56 are shown acting in advance of the helices. Ring 55 is coaxial with the helix 44 and is designed to be fitted to the corresponding roll support or bar 35 and annular gear 33. The rolling ring 56 is coaxial with

the helix 42, and is, therefore, mounted upon the bar 35 thereof. These rings may preferably do very little rolling and serve mainly as rolling guides for controlling the admission of the work piece 51 and mandrel 50. They show, however, that rings and forms of rolls other than helices may be employed in co-operation with the helices, as well as separately therefrom, as explained in connection with Fig. 8. It will be clear that the feeding effect of the rings 55 and 56 will be but slightly less than the entrance ends of the corresponding coaxial helices, and therefore they can be properly mounted on the same supports with the respective helices.

In the operation of the machine, it will be understood that the tube or work piece upon its mandrel 50 is inserted through the rolling rings 55 and 56 into the mouth or entrance end of the four helices, and, as the rolling proceeds, the work piece is cross-rolled, rotating rapidly and advancing through the machine as its wall is reduced in thickness and elongated by the rolling bodies, and it is delivered at the exit end of the machine through the hollow shaft 14.

It will be seen that by adjusting the angularly adjustable carriers 21 outward slightly, the entrance end of the pass is made smaller, and vice versa. Such an adjustment changes but slightly the angles between the axes of the rolls and the axis of the pass. Such adjustment alters the size of the exit end of the pass to a much less extent, depending somewhat on how far in the rear of the exit ends of the helices or rolls are placed the pivots 20 about which the carriers are adjustable. I prefer to arrange them as shown, which allows a slight variation in the size of the exit end of the pass and facilitates an accurate gaging of the external diameter of the tube by the machine, if desired. For any considerable variation in the diameter of the work piece, it is better to employ different sets of helices or rolls, rather than to design the machine for a wide range of adjustment with the same rolls.

It will be seen that with the arrangement of helices shown, the work piece is simultaneously embraced on four different sides at a single cross section by rolling bodies which are concave in the direction in which they roll, and, therefore, to a considerable extent embrace the work piece in a manner not possible with rolls which are barrel-shaped or otherwise convex in the planes of their rolling motion. Consequently, it will be seen that the metal of the tube can more readily flow longitudinally or elongate than if rolled between barrel-shaped or disk-shaped rolls, for example; moreover where a tube is rolled or elongated at two opposite points only, manifestly the intermediate parts of its pe-

riphery have to be stretched lengthwise to allow the elongation, and such parts tend to resist the elongation and to cause expansion. The present invention approaches the more 5 ideal condition, wherein the tube is subjected to cross rolling and elongation simultaneously all around its periphery at the same cross section.

It will be seen that the cross rolling members of my machine, whether helices or rings, are so axially positioned as to afford progressively diminishing cross rolling speed and progressively increasing longitudinal or feeding speed as the work piece diminishes in external diameter and in cross section in advancing through the pass.

It will be seen that where a rolling ring, such as 35, and a rolling helix, such as 44, are mounted rigidly together to turn about 20 a single axis, or where a plurality of rings or rolling bodies are so mounted, as, for example, in Fig. 8, they constitute a composite or compound cross rolling element which may be mounted upon a common support 25 port in a common carrier, and thereby arranged to concert with one or more similar composite rolling elements; and by the expression "cross rolling element" I mean to include such a composite element comprising two or more rolling members.

It will be clear that the invention is susceptible to great variation of form and design without departing from the principles of the invention set forth in my generic 35 claims.

I, therefore, claim and desire to secure the following:

1. In a machine for cross rolling round bodies, the combination of a plurality of 40 oblique cross rolling members which have rolling faces that are concave in the planes of their rolling motion, said members being respectively mounted with their axes offset from and oblique to the axis of the pass and being positioned to make obliquely acting 45 rolling contact with the work piece, some of the said rolling members being mounted in advance of the others in succession along the pass.

2. In a machine for cross rolling round bodies, the combination of a plurality of 50 oblique cross rolling members which have rolling faces that are concave in the planes of their rolling motion, said members being respectively mounted with their axes offset from and oblique to the axis of the pass and being positioned to make obliquely acting 55 rolling contact with the work piece, the contact faces of some of the said rolling members being disposed in oblique relation to the paths of their rolling motions, whereby their areas of contact travel along the pass during the rolling action.

3. In a machine for cross rolling round 60 bodies, the combination of several rolling

members which have rolling faces concave in the plane of their rolling motion and which make rolling contact about the work piece at more than two points around the work piece in the same transverse plane 70 through the work piece, thereby rolling it simultaneously at substantially all sides under said concave faces.

4. In a machine for cross rolling round bodies, the combination of several rolling 75 members which have rolling faces concave in the plane of their rolling motion and which make rolling contact about the work piece at more than two points around the work piece in the same transverse plane 80 through the work piece, thereby rolling it simultaneously at substantially all sides under said concave faces, said members being positioned to roll obliquely of the work piece.

5. In a machine for cross rolling round bodies, the combination of several rolling 85 members which have rolling faces concave in the plane of their rolling motion and which make rolling contact about the work 90 piece at more than two points around the work piece in the same transverse plane through the work piece, thereby rolling it 95 simultaneously at substantially all sides under said concave faces, said members being positioned to roll obliquely of the work piece and also disposed obliquely of their own motion whereby their areas of contact travel along the pass, and proportioned to give greater longitudinal feeding components of motion toward the exit end of the 100 pass.

6. In a machine for cross rolling round bodies, the combination of a plurality of 105 cross rolling members which have rolling faces concave in the planes of their rolling motions and which are positioned to make obliquely acting rolling contact with the work piece at a plurality of separated points in the length of the work piece, and proportioned and positioned to give greater end- 110 wise components of motion toward the exit end of the pass.

7. In a machine for cross rolling round bodies, the combination of a compound 115 cross rolling element which surrounds the pass and comprises a plurality of cross rolling members mounted upon a common support about a common axis offset from and at an angle to the axis of the pass, and an angularly adjustable carrier forming said common support, and one or more rolling elements coacting with the first said rolling element.

8. In a machine for cross rolling round 125 bodies, the combination of a compound cross rolling element which surrounds the pass and comprises a plurality of cross rolling members mounted upon a common support about a common axis offset from at an angle 130

- 6 to the axis of the pass, and an angularly adjustable carrier forming said common support, means for driving said members as a unit, and coöperating rolling elements 5 having driving connections therewith.
- 7 9. In a machine for cross rolling round bodies, the combination of a cross rolling helix which surrounds the pass, and means 10 for supporting and driving said helix about its own axis in position offset from and at an angle to the axis of the pass.
- 11 10. In a machine for cross rolling round bodies, the combination of a cross rolling helix which surrounds the pass, and means 15 for supporting and driving said helix about its own axis in position offset from and at an angle to the axis of the pass, said helix being positioned and proportioned to give increased feeding components of its rolling 20 motion toward the exit end of the pass.
- 11 11. In a machine for cross rolling round bodies, a plurality of successive rolling rings encircling the pass and mounted to turn on a plurality of axes oblique to each other and 25 to the pass and offset from the pass axis, said rings being positioned and adapted to give successively increasing feeding movement lengthwise of the pass.
- 12 12. In a machine for cross rolling round 30 bodies, a plurality of successive rolling rings encircling the pass and mounted to turn on a plurality of axes oblique to each other and to the pass and offset from the pass axis.
- 13 13. In a machine for cross rolling round 35 bodies, a plurality of successive rolling rings encircling the pass and mounted to turn on a plurality of axes oblique to each other and to the pass and offset from the pass axis, and 40 another plurality of rolling members positioned to act nearer the exit end of the pass.
- 14 14. In a machine for cross rolling round 45 bodies, a plurality of successive rolling rings encircling the pass and mounted to turn on a plurality of axes oblique to each other and to the pass and offset from the pass axis, and another plurality of cross rolling members 50 mounted to turn on axes coincident with those of the said rings and positioned to act on the work piece nearer the exit end of the pass.
- 15 15. In a machine for cross rolling round 55 bodies, a plurality of successive rolling rings encircling the pass and mounted to turn on a plurality of axes oblique to each other and to the pass and offset from the pass axis, and another plurality of cross rolling members 60 mounted to turn on axes coincident with those of the said rings and positioned to act on the work piece nearer the exit end of the pass and adapted to give relatively greater feeding movements.
- 16 16. In a machine for cross rolling, a plurality of angularly adjustable carriers, 65 means for supporting said carriers, one or
- more cross rolling members supported by each of said carriers and turning in paths encircling the work piece.
- 17 17. In a machine for cross rolling, a plurality of angularly adjustable carriers, 70 means for supporting said carriers, one or more cross rolling members supported by each of said carriers and turning in paths encircling the work piece, shafts mounted in the said carriers and geared to the said rolling members, and means for driving the said shafts.
- 18 18. In a machine for cross rolling, a plurality of angularly adjustable carriers, 75 means for supporting said carriers, one or more cross rolling members supported by each of said carriers and turning in paths encircling the work piece, annular gears for the said rolling members having bearings on the said carriers, and coacting driving gears 80 for the same, and means for driving the said driving gears.
- 19 19. In a machine for cross rolling, a plurality of angularly adjustable carriers, 85 means for supporting said carriers, one or more cross rolling members supported by each of said carriers and turning in paths encircling the work piece, the axes of said paths lying at a plurality of different positions offset from and oblique to the axis of 90 the pass.
- 20 20. In a machine for cross rolling round 95 bodies, the combination of a frame, a plurality of carriers angularly adjustable on the said frame, a plurality of rolling bodies 100 carried by the said carriers and forming a pass, shafts mounted on each of the carriers for actuating the rolling bodies and angularly adjustable with the carriers, driven gears mounted on and turning the respective shafts, and a gear for driving them, the projected axial lines of the said shafts converging substantially to intersect the projected axis of the pass and the axes of the rolling 105 bodies being parallel with the corresponding shafts but offset from the axis of the pass.
- 21 21. In a machine for cross rolling round 110 bodies, the combination of a frame, a plurality of carriers angularly adjustable on the said frame, a plurality of rolling bodies 115 carried by the said carriers and forming a pass, shafts mounted on each of the carriers for actuating the rolling bodies and angularly adjustable with the carriers, driven gears mounted on and turning the respective shafts, and a gear for driving them, said carriers having pivotal connections with the frame and having screw adjusting means 120 for adjusting and rigidly holding them.
- 22 22. In a machine for cross rolling round 125 bodies, the combination of a plurality of cross rolling members acting progressively along the pass, each of the said rolling members being mounted upon an axis oblique to and offset from the axis of the pass, the 130

paths of motion of the rolling faces of the said rolling members encircling the work piece.

23. In a machine for cross rolling round bodies, the combination of a plurality of cross rolling members acting progressively along the pass, each of the said rolling members being mounted upon an axis oblique to and offset from the axis of the pass, the paths of motion of the rolling faces of the said rolling members encircling the work piece, and means for driving the said members.

24. In a machine for cross rolling round bodies, the combination of a plurality of cross rolling members acting progressively along the pass, each of the said rolling members being mounted upon an axis oblique to and offset from the axis of the pass, the paths of motion of the rolling faces of the said rolling members encircling the work piece, and means for driving the said members to vary the size of the pass formed by them.

25. In a machine for cross rolling round bodies, the combination of a plurality of cross rolling members, each of the said rolling members being mounted upon an axis oblique to and offset from the axis of the pass, the paths of motion of the rolling faces of the said rolling members encircling the work piece, and means for angularly adjusting the said members.

26. In a machine for cross rolling round bodies, a plurality of successively arranged concave rolling bodies the paths of motions of which encircle the pass, said bodies being mounted to turn upon a plurality of axes which are oblique to each other and to the pass and which are offset from the pass.

27. In a machine for cross rolling round bodies, the combination of a plurality of oblique cross rolling members which have rolling faces that are concave in the planes of their rolling motions, and the paths of motions of which encircle the pass, said members being mounted with their axes offset from and oblique to the axis of the pass and positioned to make obliquely acting rolling contact with the work piece, and a mandrel adapted for coöperation in the said pass with the said rolling members, whereby the work piece may be subjected to oblique rolling between said concave faces and the mandrel.

28. In a machine for cross rolling and reducing the wall thickness of tubes upon mandrel bars, the combination of a mandrel and two cross rolling rings which have narrow rolling faces that are concave in the planes of their rolling motion and are mounted upon axes offset to each other and to the axis of the mandrel when in its working position and are inclined at an angle to the said axis of the mandrel, the obliquity and the eccentricity of the axes being such that a substantial longitudinal feeding component of the rolling motion is produced by the rings, the paths of motion of the rolling faces of the rings encircling the mandrel and the centers of rotation of the respective rings being located in different planes perpendicular to the axis of the mandrel.

In testimony whereof I have signed this specification in the presence of two subscribers this 9th day of July, 1912.

LEONARD D. DAVIS.
